US00D611642S

(12) **United States Design Patent**
Sieczkowski et al.

(10) **Patent No.:** US D611,642 S
(45) **Date of Patent:** ** Mar. 9, 2010

(54) **LIGHT FIXTURE**

(75) Inventors: **Philip Sieczkowski**, Lawrenceville, GA (US); **James P. Compton**, Conyers, GA (US)

(73) Assignee: **ABL IP Holding LLC**, Conyers, GA (US)

(**) Term: **14 Years**

(21) Appl. No.: **29/340,098**

(22) Filed: **Jul. 14, 2009**

(51) **LOC (9) Cl.** **26-05**

(52) **U.S. Cl.** **D26/74**

(58) **Field of Classification Search** D26/26,
D26/37, 67, 72, 74-79, 80, 85, 104, 108,
D26/118, 120, 122, 134; 362/147-148, 150,
362/217-225, 132, 260, 262-264, 267, 294,
362/345, 362, 364, 373, 376, 440

See application file for complete search history.

CLAIM

The ornamental design for a light fixture, as shown and described.

DESCRIPTION

FIG. 1 shows a bottom perspective view of a light fixture, showing our new design.

FIG. 2 shows a right side elevation view of the light fixture of FIG. 1, the left side elevation view being identical to the right side elevation view.

FIG. 3 shows a front elevation view of the light fixture of FIG. 1, the rear elevation view being identical to the front elevation view; and,

FIG. 4 shows a bottom plan view of the light fixture of FIG. 1. Portions or features of the light fixture not shown in the drawings form no part of the claimed design. The broken lines in the drawings form no part of the claimed design.

1 Claim, 3 Drawing Sheets
